UNITED STATES PATENT OFFICE.

EDWARD BRUNHOFF, OF CINCINNATI, OHIO.

DESIGN FOR A CHANGE-TRAY.

43,517.

Specification for Design.

Patented Feb. 11, 1913.

Application filed July 1, 1911. Serial No. 636,548. Term of patent 7 years.

To all whom it may concern:

Be it known that I, EDWARD BRUNHOFF, a citizen of the United States, residing at Cincinnati, in the county of Hamilton and State of Ohio, have invented a new, original, and ornamental Design for Change-Trays, of which the following is a specification, reference being had to the accompanying drawings, forming a part thereof.

My new and original design comprises, as illustrated a hollow transparent body exteriorly of the form of a frustum of a cone with the upper plane face inclined relative to the plane of the base, there being a concavity or depression at the lower portion of the upper face or inclined plane, and a raised rib or ring surrounding said inclined plane, which is of greater depth at the lower

edge of said inclined plane than at its upper edge. Colors are applied to the inner face of the body to show through the body walls, which due to the polished surface of the body presents a particularly bright and pleasing effect, and the effect of a solid body. The upper or inclined plane is also designed to display advertising matter.

I claim:

The ornamental design for a change tray as shown and described.

In testimony whereof I have affixed my signature in the presence of two witnesses.

EDWARD BRUNHOFF.

Witnesses:

C. W. MILES,
W. THORNTON BOGERT.
